(57) **CLAIM**

The ornamental design for a vehicle wheel, as shown and described.

DESCRIPTION

FIG. 1 is a front elevational view of a vehicle wheel showing our new design; and,

FIG. 2 is a perspective view thereof.

The claimed design is indicated by the relatively dark portions in the figures. The de-emphasized and relatively light portions form no part of the claimed design.

1 Claim, 2 Drawing Sheets Fig. 1
